COIN-CONTROLLED MECHANISM

Harry S. Childers, Fresno, Calif., assignor to
 Vendorlator Manufacturing Company, Fresno,
 Calif.

Application January 14, 1949, Serial No. 70,994

13 Claims. (Cl. 194—80)

1

This invention relates generally to coin operated vending machines and more particularly to an improved coin detector and change making mechanism.

Briefly described, the invention comprises means for mechanically rejecting a coin inserted in a change making vending machine when there are insufficient coins remaining in the machine to make proper change for the coin deposited.

In change makers there is provided a vertically positioned tube adapted to receive coins on operation of the vending machine which coins are dispensed from the machine in making change, when the machine is operated with coins of larger denomination, requiring change. The coins must lie horizontally in the tube in a vertical stack for proper operation of the change maker. Coin detectors, heretofore provided for vending machines, have means extending into the coin tube and engage the edges of coins falling therein. Such means tend to tip each coin inserted thus precluding proper loading and operation of the coin tube.

When there is a sufficient number of coins in the coin tube for making desired change, the coin detector is urged out of the tube by an inserted coin preconditioning the vending machine for operation and change making. When the number of coins in the coin tube is reduced to an insufficient number for making desired change, the coin detector is positioned to reject inserted coins and to lock the vending machine against operation.

Other change making mechanisms have been provided for vending machines for detecting when there are insufficient coins in the machine to make proper change but these have been electrically operated with intricate electrical switches, actuators and electrical operating circuits which frequently get out of order and are a source of considerable expense. These electrically operated coin detectors are not only expensive to manufacture and difficult to assemble, but are not dependable in their operation. Such switches operate by the weight of a coin imposed thereon, which weight is insufficient to operate mechanical detectors and in many instances insufficient dependably to operate the electrical switches.

Therefore, it is an object of the present in-

2

vention to provide a coin changing mechanism for vending machines which is dependable in detecting the presence and absence of change making coins in desired quantity.

Another object of the invention is to provide a coin detector mechanism which does not impede the proper horizontal locating and vertical stacking of the change coins as they fall into a coin tube.

10 Another object is to provide means for withdrawing a coin detector finger from the change making coin tube during the period of time that a coin is gravitating into the tube.

Another object of the invention is to provide 15 a dependable mechanical means for preventing operation of a change making device when the change making magazine contains an insufficient number of coins for the making of change.

Another object is to provide a coin detector 20 that is responsive to coin position independent of the weight of the coin.

A still further object is to provide a coin detector that is economical to manufacture, easy to assemble, and is dependably automatic in its 25 operation.

Other objects and advantages of the present invention will become apparent in the following description.

In the drawings:

30 Fig. 1 is a front elevational view of a coin responsive mechanism of a type employed in vending machines to release a vending mechanism and to make change in which is shown a coin detector of the construction of the present invention. A portion of the housing of the mechanism is removed for illustrative convenience.

35 Fig. 2 is a vertical somewhat enlarged, fragmentary, lateral sectional view through the mechanism illustrated in Fig. 1 of the drawings.

40 Fig. 3 is a fragmentary, vertical, transverse section through an upper portion of the coin responsive mechanism showing a coin-detector-operated coin rejecting mechanism therefor, in 45 coin rejecting position, taken along line 3—3 in Fig. 2.

Fig. 4 is a view similar to Fig. 3 but showing the coin rejecting mechanism in coin admitting position.

50 Fig. 5 is a horizontal sectional view through

3

the coin responsive mechanism, taken along line 5—5 in Fig. 2.

Fig. 6 is a fragmentary, vertical, transverse section through the lower portion of the coin responsive mechanism, as taken along line 6—6 in Fig. 5 but with the slide movement to the left.

Figs. 7 and 8 are fragmentary, vertical, transverse sections through the lower portion of the vending machine taken along lines 7—7 and 10 8—8, respectively, in Fig. 5.

Fig. 9 is a fragmentary, vertical, transverse section through the lower portion of the vending machine and through a portion of the coin tube, taken along line 9—9 in Fig. 5, showing the 15 coin detector in retracted position as held by a sufficient coin supply.

Fig. 10 is a view similar to Fig. 9 but showing the coin detector in retracted position as when coins are received by the coin tube.

Fig. 11 is a view similar to Fig. 9, but showing the coin detector in a position extending into the coin tube.

The essence of the present invention resides in the provision of means in a coin change making and/or vending mechanism that locks the mechanism against operation when there is less than a predetermined quantity of coins in the mechanism for change making purposes, that rejects coins of a denomination for which there is an insufficient quantity of coins in the mechanism for change making purposes while accepting coins of smaller denomination, which employs coins of various denomination to interlock change making means, and which in determining the quantity of coins in the mechanism available for change making purposes contacts such coins while they are at rest and thus avoids interference with coin movement and stacked accumulation in a change accumulating magazine. The device of the present invention is best understood in its operational environment. Thus preliminary attention is devoted to an explanation of the environment which is provided for illustrative purposes and not by way of limitation.

Referring in greater detail to the construction as illustrated in the drawings and more particularly to Fig. 1, the coin responsive mechanism, with which the coin detector of the present invention is employed, comprises a rectangular casing 10 enclosing a housing, indicated generally by the reference numeral 11, having a back plate 12 and an upper compartment 13 partially enclosed by parallel side plates 14 formed integrally with the back plate and extending forwardly therefrom. A lower compartment 16 is partially enclosed by parallel side plates 17 formed integrally with the back plate 12 and extending forwardly therefrom. The lower compartment 16 is also provided with a bottom plate 18 attached to and extending horizontally between the lower edges 60 of the side plates 17.

The upper compartment 13 contains a slug rejecting mechanism 19 of a well-known design which is adapted to accept and pass coins therethrough. The slug rejector in this instance is designed to accept nickels, dimes and quarters through an entrance 20, for conditioning a vending machine for vending operation. The slug rejector is also designed to reject dimes and quarters when there is an insufficient number of 70 nickels in a coin magazine for making change.

The vending machine, conditioned for operation by the present invention, is constructed to vend objects such as bottled beverages in response to the insertion of a nickel, dime or quarter and 75

4

to reject all spurious objects. When a dime or quarter is inserted into the vending machine, the machine is adapted to vend the desired commodity and the appropriate change. Whenever there is an insufficient number of nickels in the coin mechanism for making change, the dimes and quarters inserted into the slug rejector are returned by a mechanism hereinafter described and no vending operation performed.

Each nickel that is deposited or inserted at 20 into the slug rejector 19, falls through the rejector, along the dash line indicated by the reference numeral 21 and precipitates from the lower right hand corner of the rejector, as viewed in Fig. 1 of the drawing. Each ten cent coin or dime that is inserted into the rejector falls through the rejector along the dash-dot line, indicated by the reference numeral 22, and precipitates from the lower right hand corner of the rejector. Each quarter that is deposited into the slug rejector falls through the rejector along the dash-dot-dot line, indicated by the reference numeral 24, and precipitates from the rejector at its lower right hand corner. The segregation of the nickels, dimes, and quarters is accomplished in any convenient manner, conventional or otherwise, and is not described in greater detail.

The coin mechanism is provided with a horizontally extending vending machine operating shaft 26 which is rotatably mounted between the back plate 12 and a front plate 27 attached at 28 in spaced parallel relation to the back plate. On rotation of the shaft 26 sufficiently, an article of merchandise, such as a bottled beverage, is vend- 30 ed from a vending machine, not shown, associated with the coin mechanism of the present invention. The shaft 26 is manually operable by means of a lever 29 attached to and extending radially from the shaft. A plurality of vertically 35 extending slots 30 are formed through a disk 31 attached in concentric relation to the shaft 26. Each of the slots 30 is adapted to receive a coin of a predetermined denomination and to guide the coin downwardly as it precipitates to its proper 40 position.

Nickels passing through their individual slot 30 in the disk 31 are guided into the upper end of a vertically positioned cylindrical coin tube 35. Whenever the coin tube becomes filled, all nickels subsequently descending to the tube thereafter fall into the upper end of an overflow chute 36 which is attached at 37 to one of the side plates 17. All dimes passing through their individual slot 30 in the disk 31 are guided by the disk into the upper end of a dime coin chute 39 and gravitate downwardly to the lower end of the chute. All quarters passing through their respective slot 30 in the disk 31 precipitate into the upper end of a quarter coin chute 40 and gravitate to the lower end of the chute.

A slide mechanism, indicated generally by the reference numeral 44 in Figs. 1 and 2, is provided with a pair of spaced parallel longitudinal slide guides 46 which are attached to the upper side of the bottom plate 18 by means of a plurality of screws 47. A coin tube supporting plate 48 extends horizontally between and is attached by means of screws 50 to the spaced slide guides 46. The nickel coin tube 35 extends downwardly into and is secured to the supporting plate 48. An operating slide 52 is slidably guided horizontally and longitudinally between the slide guides 46 and has a dime slot 53 and a longitudinally spaced quarter slot 54 formed vertically through and extending transversely of the operating slide. Said slots are adapted to receive their respective

coins on edge as they descend from their respective chutes 39 and 40.

A dime operable slide 56 is longitudinally slidably guided between the slide guides 46 with a portion of the operating slide 52 overlapping or superimposed on a portion of the dime slide. The dime slide has a dime slot 57, and a quarter slot 58 longitudinally spaced therefrom, formed vertically and transversely through the dime slide to receive their respective coins on edge, as shown in Fig. 2. The dime slide 56 also has a nickel receiving pocket 59 formed vertically therethrough which is normally located under the lower end of the nickel coin tube 35 and is adapted to receive individual nickels from the coin tube. A quarter operable slide 62 is longitudinally slidably guided between the slide guides 46 with a portion of the quarter slide superimposed on a portion of both the operating slide 52 and the dime slide 56. The quarter operable slide 62 has a quarter receiving slot 63 formed vertically and transversely therethrough and a cylindrical pocket 64 formed vertically therethrough, adapted to contain three nickels received from the bottom of the coin tube.

The dime coin slots 53 and 57 are normally in vertical alignment directly beneath the lower end of the dime chute 39 adapted to receive a dime from the dime coin chute vertically therein against the upper side of the bottom plate 18, providing horizontal driving connection between the operating slide 52 and the dime operable slide 56. The quarter slots 63, 54, and 58, when their respective members are at rest, are located in vertical alignment directly beneath the lower end of the quarter chute 40 adapted to receive a quarter vertically therein rested on the bottom plate 18 and providing horizontal driving connection between the operating slide and both the dime operated slide 56 and the quarter operated slide 62.

The pocket 59, in the dime slide, and the pocket 64, in the quarter slide, are located, when their respective members are at rest, in vertical alignment directly beneath the lower end of the nickel coin tube 35 adapted to receive nickels gravitationally from the coin tube.

The bottom plate 18 of the lower compartment 16 is provided with a cylindrical passage 67 formed vertically therethrough through which coins are adapted to gravitate from the pockets 59 and 64 in the dime operated slide 56 and the quarter operated slide 62, respectively. A change receptacle 68 is secured to the underside of the bottom plate 18 in vertical alignment with the passage 67 located to receive change making nickels from the pockets 59 and 64. The bottom plate 18 has a dime depositing slot 70 and a longitudinally spaced quarter depositing slot 72 formed vertically and transversely therethrough located above a removable coin depositing box 73 supported on a portion of the case 10 of the coin mechanism. The slots 70 and 72 are adapted respectively to receive individual dimes and quarters therethrough when either of the aligned dime slots 53 and 57 or the aligned quarter slots 54, 58 and 63 are located in vertical alignment therewith thus depositing the coins therefrom into the coin depositing box 73.

Means are provided by movement thereof for actuating the operating slide 52 horizontally to the left, as viewed in Fig. 2 of the drawing, from its normal rest position to coin depositing position. This means comprises a cam member 75 attached to the shaft 26 having a cam slot 76 formed horizontally through the member. A lever 85 is pivotally connected at 86 to a portion

of the housing 11 and has a cam follower 87 rotatably connected to one end of the lever and guidably received into the cam slot 76 and movable thereby. A pin 88 is secured to the opposite end of the lever 85 which is located in a slot 90 formed through one end of a link 91. The other end of the link 91 is pivotally connected at 92 to the upper end of a lever 94 which in turn is pivotally connected at 95 to the back plate 12 of the housing. A helical tension spring 96 is connected at one end to one of the side plates 17 of the lower compartment and connected at its other end to the pivotal connection 92 so that the lever 94 and coating members are yieldably held in their normal rest positions as illustrated in Fig. 2 of the drawings. The lower end of the lever 94 is provided with a circular head 97 which extends downwardly into a cylindrical opening 98 formed vertically through the operating slide 52 so that the lever 94 and the operating slide 52 are operatively associated.

Means are provided for locking the vending machine operating shaft 26 against sufficient rotation to operate the vending machine when no coin or a spurious object is deposited in the mechanism. As shown in Fig. 2, this means comprises an approximately circular latch plate 99 secured concentrically to the vending machine operating shaft 26 and having a notched or hooked portion 100 formed in the periphery thereof. A roller 101 is rotatably mounted at the outer end of a lever 102 rotatably mounted on a shaft 103 extending horizontally between the back plate 12 of the housing and the front plate 27 of the lower compartment in a position to engage the latch plate hook 100 upon rotation of the latch plate from its normal rest position, as for vending purposes. Another lever 106 is pivotally mounted on the shaft 103 in operative contact with the lever 102 with the upper end of a rod 107 pivotally connected at 108 to its outer end. Referring to Fig. 6, the lower end of the rod 107 is pivotally connected at 109 to a leg of a bell crank lever 111 which is pivotally mounted at 112 to the back plate 12 of the housing. A substantially horizontally located rod 113 is pivotally connected at 114 to the opposite leg of the bell crank lever with the opposite end of the rod connected to one end of a pin 115 which is secured horizontally through the dime operable slide 56. The pin 115 extends through a pair of relatively horizontally located slots 116 formed horizontally and transversely of the slide guides 46. A knob 117 is secured to the outer end of the pin 115 so that the dime operable slide may be moved manually by a service man, a repair man, or other person having access to the knob, by manually reciprocating the slide and unloading the coin tube.

A coin rejecting lever 120, as shown in Figs. 2, 3, and 4 of the drawings, is located adjacent the rear side of the slug rejector 19 within the upper compartment 13 and is pivotally mounted at 121 on a bracket 122 secured to the forward face of the back plate 12 of the housing. This coin rejecting lever 120 is provided with a quarter rejecting finger 124 and a dime rejecting finger 125 adapted to extend into the path 24 of the quarters and the path 22 of the dimes, respectively, to divert their respective coins, when extended into said path causing the contacted coins to be rejected from the slug rejector out of the lower left hand corner thereof, as viewed in Fig. 1 of the drawing and returned to the operator of the machine. The coin rejecting lever 120 is provided with an integral upwardly extending short leg 127 with a tension spring 128 connected be-

tween the leg and the bracket 122 yieldably urging the coin rejecting lever to coin diverting position. The coin rejecting lever 120 is movable to inoperative or ineffective position by means of a short arm 130 formed integrally with the coin rejecting lever 120 and rearwardly extended therefrom. A substantially vertically located rod 131 is slidably extended upwardly through an opening formed through the arm 130. A collar 133 is secured in circumscribing relation to the rod 131 which engages the under side of the arm 130 on upward actuation of the rod 131 moving the coin rejecting lever 120 to ineffective or retracted position.

The coin detector mechanism of the present invention, as is best shown in Figs. 5, 9, 10, and 11 of the drawings, comprises a coin detector finger 135 pivotally mounted at 136 to a bracket 137 secured in circumscribing relation to the coin tube 35. The coin detector finger is provided with a substantially horizontally extending arm 138 with the lower end of the rod 131 pivotally connected at 139 to the outer end thereof. The finger is also provided with a downwardly extending, triangular portion 140 adapted to enter into the lower end of the coin tube 35 through a slot 141 formed vertically through the lower end thereof. The weight of the rod 131 and the arm 138 of the coin detector plate 135 urges the finger rotatably around its pivot 136 in a counterclockwise direction, as viewed in Figs. 9, 10, and 11, to extend the triangular portion 140 into the lower end of the coin tube 35 through the slot 141.

As nickels are received into the upper end of the coin tube they precipitate into the pocket 59 of the dime slide 56 and into the pocket 64 in the quarter slide 62 and when the stack of nickels is of such a height that there are nickels located adjacent the lower end of the triangular portion 140 of the finger, the finger is retained in a partially withdrawn position by abutment with the near edges of the nickels stacked in the coin tube to a predetermined height.

Means are provided for moving the triangular portion 140 of the finger to a fully withdrawn position exteriorly of the lower end of the coin tube 35 during the period that a coin is precipitated into the coin tube so that the coin detector finger will not interfere with the fall of the coin. This is significant in that any interference or contact with a coin descending into the tube has been found to tip the coin and frequently to lodge coins on edge in the magazine. The means for withdrawing the triangular plate portion 140 of the coin detector finger comprise a substantially horizontally located slide rod 145 located adjacent the back plate 12 of the coin mechanism which is guided for longitudinal sliding motion in a pair of guide brackets 146 each of which is screwed at 147 to the back plate. The slide rod is bent upwardly forming a cam portion 148 and thence to a horizontal position forming a horizontally located raised portion 149 at the end of the slide rod adjacent to the coin tube. The slide rod is bent to a horizontal forwardly extending portion 150 which is secured transversely through the outer end of the operating slide 52 with the rod portion 150 guided for horizontal sliding motion in a pair of relatively horizontally located slots 151 formed horizontally and longitudinally in each of the slide guides 46. The arm 138 of the coin detector finger 135 rests on the upper side of the slide rod 145, at rest in the position as shown in Fig. 2 of the drawings at the lower end of the cam portion 148. In this position the portion 140 of the cam detector finger extends into

the coin tube. The triangular plate portion 140 of the coin detector finger is moved to fully withdrawn position exteriorly of the lower end of the coin tube 35 by horizontal longitudinal sliding motion of the slide rod 145 on horizontal longitudinal sliding motion of the operating slide 52 actuated on rotation of the operating lever 29 and shaft 26 by means of the cam slot 76, cam follower 87, lever 85, link 91, and the lever 94 connected to the operating slide 52.

Operation

In the operation of the coin detecting mechanism as shown and described, the mechanism 15 may be operated by the insertion of the nickel or five-cent coin into the upper end of the slug 20 rejector 19 with the nickel gravitating through the slug rejector along the dash line 21, indicated in Fig. 1 of the drawings, and moving to the lower right hand corner of the slug rejector. The nickel gravitates downwardly from the slug rejector into one of the slots 30 in the disc 31, with the upper arcuate edge of the nickel engaging partially under the roller 101 on the lever 102 as shown in Fig. 2 of the drawings. The vending machine operating lever 29 is manually rotated in a downward, or clockwise, direction as viewed in Fig. 1, which causes the periphery of the nickel lodged in the slot 30 of the disc 31 to cam the roller 101 outwardly relative to the operating shaft 26 thereby freeing the roller from the hooked portion 100 and the shaft for continued rotation, as for a complete vending or change making cycle. The continued clockwise rotation of the shaft 26 pivots the lever 85 which, through the link 91 and the lever 94, urges the slide 52 to the left, as viewed in Fig. 2. Somewhat similarly, if there is no nickel in the slot 35 30 but there is a dime or a quarter in its respective slot in the slides, initial rotation of the lever 40 moves the dime slide 56 to the left and through the bell crank lever 111 lowers the rod 107 and removes the roller 101 from engagement with hooked portion 100 freeing the shaft for a complete vending or change making cycle. Moving 45 the operating slide 52 to the left also moves the slide rod 145 to the left, moving the cam portion 148 of the slide 145, camming the arm 138 of the coin detector finger upwardly and pivoting the coin detector plate to fully withdrawn position from the lower end of the coin tube 35. Movement of the dime slide 56 to the left, through the action of the pin 115 and the rod 113, pivots the bell crank lever 111, lowers the rod 107, and 50 pivots the lever 106 urging the lever 102 clockwise to a position retracting the roller 101 from hook engagement. The interconnection of the lever 85 and the link 91 by means of reception of the pin 88 in the slot 90 permits the emptying 55 of the coin tube by manual reciprocation of the slide by the knob 117 without interference to movement by hook 100 and roller 101 engagement. On further rotation of the operating lever 60 65 29, the periphery of the disc 99 engages under the roller 101 holding the arm 102 to its clockwise pivoted position while the nickel gravitates from the slot 30 downwardly into the coin tube. As the nickel gravitates downwardly into the coin tube the triangular plate portion 140 of the coin detector finger 135 is in withdrawn position so that it will not interfere with the natural fall of the coin into the tube and permits the coin to fall to a horizontal position on the uppermost coin of the stack of coins in the coin tube. On 70 75 full operative rotation of the operating lever

29 and the operating shaft 26, the vending machine operatively connected thereto vends a five-cent article of merchandise, such as bottled beverages.

The vending machine may be also operated with coins of denominations larger than five cents, such as with a dime or quarter, in which instance the five-cent article is vended from the machine and change of the proper amount, in nickels, is delivered to the customer. Whenever it is necessary or desirable to operate the vending machine with a dime, the coin is inserted in the upper portion of the slug rejector 19 and gravitates downwardly along the dot-dash line, indicated at 22, in Fig. 1 of the drawing, and is normally delivered out of the lower right hand corner of the slug rejector. Whenever the dime rejecting finger 125 of the coin rejecting lever 120 is inserted into the path of the dime gravitating through the slug rejector 19, the dime is diverted and rejected out of the lower left hand corner of the slug rejector and is returned to the operator of the machine. If the dime is accepted by the slug rejector, it gravitates downwardly through one of the slots 30 in the disc 31 into the upper end of the dime chute 39 falling downwardly therethrough and is guided by the dime chute 39 into the vertically aligned dime slots 53 and 57 formed respectively in the operating slide 52 and the dime slide 56. With the dime thus located in the dime slots 53 and 57, movement of the operating slide 52 also causes movement of the dime slide 56 having driven connection therewith by means of the dime extending therebetween. On downward or clockwise rotation of the vending machine operating lever 29 and operating shaft 26, the initial rotation thereof moves the roller 101 radially outwardly from the operating shaft 26 to a position out of the rotative path of the notch 100 in the disc 99 through the movement of the operating slide moving the dime slide 56 by means of the rods 107 through the pivoted bell crank lever 111 operatively connected to the lever 102. With the roller 101 thus moved out of the path of the hooked portion 100 of the disc 99, the operating lever 29 may be rotated as for a vending cycle. During such operation the operating slide 52 and the dime slide 56 are moved longitudinally to coin releasing position through the rotative operation of the disc 75, cam slot 76, cam follower 87, lever 85, link 91, and lever 94 operatively associated with the operating slide 52. On sliding motion of the dime slide 56 to the left, the pocket 59 thereof, adapted to contain only one nickel, moves from a position under the coin tube to a position over the change receptacle 68 so that the nickel in the pocket 59 gravitates from the pocket downwardly into the change receptacle 68, which nickel is available to the operator of the vending machine as change for the dime deposited into the machine for the five-cent article of merchandise vended from the machine.

When the vending machine operating lever 29 has been rotated downwardly or clockwise to its fullest extent, the dime slots 53 and 57 are located over the dime depositing slot 70 in the bottom plate but with the dime still pinched in driving association between the dime slots 53 and 57. On the initial return upward motion, or counter-clockwise rotation of the operating lever 29, the operating slide 52 is initially moved slightly inwardly, releasing the pinching action on the dime and permitting the dime to fall downwardly

through the dime depositing slot 70 into the coin depositing box 73.

The machine is somewhat similarly operated by the use of a quarter, with the vending machine 5 vending a five-cent article of merchandise and returning four nickels in change therefor. The quarter is inserted into the upper portion of the slug rejector 19 and normally follows the dot-dot-dash line 24 as shown in Fig. 1 of the drawing. 10 Whenever the quarter rejecting finger 124 is located in a position projecting into the slug rejector 19 in the path of the quarter, the quarter is diverted from its normal path and rejected to the lower left hand corner of the slug rejector and 15 returned to the operator of the vending machine. When accepted by the slug rejector 19, the quarter precipitates downwardly from the lower right hand corner of the slug rejector into one of the slots 30 forward in the disc 31 and precipitates 20 downwardly into the quarter chute 40 and is guided downwardly into the quarter slots 58, 54, and 63 formed respectively in the dime slide 56, operating slide 52, and quarter slide 62. With the quarter located in the quarter slots 58, 54, and 63, 25 on initial operative rotation of the operating lever 29, the shaft 26, through levers 85 and 94 with the link 91 connected therebetween, and the operating slide 52 drivingly connected to the dime slide 56 by means of the quarter in the quarter 30 slots thereof, the dime slide 56 is moved longitudinally and horizontally to the left, as viewed in Fig. 2 of the drawings. Initial horizontal motion of the dime slide 56 actuates the lever 102 by means of the rods 107 and 113 moving the roller 101 out of the rotative path of the notch 100 35 formed in the disc 99 so that the vending machine operating lever 29 may be rotated downwardly or clockwise to vending position. On movement of the operating slide 52 to change making position, 40 both the dime slide 56 and the quarter slide 62 move horizontally therewith by means of the quarter located in the vertically aligned quarter slots of the slides. As the slides move horizontally 45 the pocket 64 of the quarter slide and the pocket 59 of the dime slide, together containing four nickels for making change, are moved over the change receptacle 68 and the appropriate change deposited. The quarter is released and deposited 50 through the slot 72 into the coin depositing box 73 located therebelow upon initial counterrotation of the shaft 26 as described for the dime release. 55 It will be noted that when either a dime or a quarter is located respectively in the vertically aligned dime slots 53 and 57 or the vertically aligned quarter slots 58, 54, and 63, that on initial movement of the operating slide 52, by rotation of the vending machine operating lever 29, that the roller 101 is rotated out of the path of the notch 100 in the disc 99 permitting the vending 60 machine to be operated to vend articles from the vending machine. It will further be noted that the vending machine operating lever 29 may be rotated initially through a small arc until the notch 100 engages the roller 101 and during this 65 rotative motion the operating slide 52 is moved horizontally sufficiently to cause the cam portion 138 of the slide rod 145 to raise the arm 138 of the coin detecting finger 135 so that the triangular plate portion 140 of the coin detector finger 70 is moved to fully withdrawn position and the collar 133 on the rod 131 moved upwardly rotating the coin rejecting lever 120 to withdrawn position 75 with the quarter rejecting finger 124 and the dime rejecting finger 125 removed from the slug rejector 19. This rotation of the coin detector

finger 135 moving the triangular plate portion 140 thereof to withdrawn position permits nickels deposited into the coin tube to gravitate therein unhampered by the presence of the coin detector finger therein so that each coin may lie flatly against the stack of coins in the coin tube.

If there is an insufficient number of coins in the coin tube, that is, when the uppermost coin in the coin tube is below the level of the lower end of the triangular plate portion 140 of the coin detector finger, on return of the operating lever 29 and operating slide 52 to normal rest position, the triangular plate portion 140 moves interiorly of the coin tube causing the rod 130 to move downwardly and permitting the coin rejecting lever 120, through the urgency of the spring 128 to rotate to effective position with the fingers 124 and 125 projecting into the slug rejector 19. Thus when the quantity of change-making nickels within the coin tube is insufficient for making change, the fingers 124 and 125, located in the slug rejector, cause all dimes and quarters inserted into the rejector to be rejected to the left of the slug rejector and returned to the operator of the machine.

Whenever the lever 29 is moved sufficiently for the lock 100 to pass the roller 101, the coin detector finger 135 is withdrawn from the coin tube 35 until the lever is returned toward normal rest position. As previously described, this permits the unimpeded fall of nickels into the coin tube. When the lever is returned to rest position, the coin detector finger 135 is released for pivotal movement into the coin tube under the urging of the weight of the rod 131 imposed thereon, as shown in Fig. 7. If there is a sufficient number of nickels in the tube 35 to make the appropriate change, the finger rests against the edges of such coins and is blocked from the coin tube. In this position, the coin rejecting fingers 124 and 125 are retracted and the mechanism is preconditioned for the acceptance of dimes and quarters as well as nickels. As shown in Fig. 9, when there is less than the predetermined number of nickels in the coin tube 35, the coin detector finger pivots into the coin tube, releasing the coin rejecting fingers 124 and 125 by the lowering of the collar 133, for movement into the dime and quarter paths, 22 and 24 respectively, under the urging of the spring 128.

From the foregoing description it will be seen that the present invention provides means in a coin responsive mechanism for rejecting coins when there is less than a predetermined number of coins in the mechanism as in rejecting coins in a change making device when there is an insufficient number of coins to make appropriate change. The coin detector of the present invention also provides means for accepting a dime or a quarter in the mechanism whenever there is a sufficient quantity of coins within the mechanism for making appropriate change. The coin detector also provides means for preventing interference with the natural fall of coins or nickels into the coin tube so that they will lie flatly and horizontally against coins already in the coin tube. It is emphasized that the nickels in the coin tube 35 do not operate the detector finger 135 but that the detector finger is positively withdrawn from the coin tube by movement of the slide rod 145 and permitted to return to the coin tube upon return of the slide rod to at-rest position only in the event less than the predetermined number of nickels are in the coin tube. The nickels have

the effect of blocking return of the finger rather than operating said finger.

Although I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices and systems.

Having described my invention, what I claim as new and desire to secure by Letters Patent is:

1. In a change making mechanism having a magazine adapted to contain coins for change making purposes, receiving means for coins for which change is to be made, and means for withdrawing a predetermined quantity of coins from the magazine in response to insertion of a coin in the receiving means reciprocally positioned between the magazine and a coin releasing position; the combination of a detector pivotally mounted for oscillatory movement between a position within the magazine and a position removed therefrom eccentrically of its center of balance and gravitationally urged to the position within the magazine, a cam member having driven connection with the withdrawing means engaged with the detector and retracting the detector from the magazine upon movement of the withdrawing means to coin releasing position, a rejector finger mounted for reciprocal movement between a position in blocking relation to the receiving means and a position removed therefrom, and a linkage interconnecting the detector and the rejecting finger and positioning said rejecting finger in blocking relation to the receiving means when the detector is positioned within the magazine, the detector being blocked from the magazine by coins in excess of a predetermined number contained by the magazine.

2. In combination with a coin magazine having a downwardly disposed opening, a plurality of change slides mounted in stacked relation below the magazine for independent reciprocal movement between coin receiving and coin releasing position and having pockets formed individually therethrough in positions simultaneously registrable with the opening in the magazine when the slides are in coin receiving position, a bottom plate slidably receiving the change slides thereon, said plate forming a bottom to the pockets when the plates are in rest position and providing a discharge opening in registry with the pockets when the slides are in coin releasing positions, an operating slide member mounted for reciprocal movement in stacked relation to the change slides, said change slides and slide member having coin slots formed therein adapted to receive coins of predetermined denominations in registration when the slide member and slides are in coin receiving position with the pockets of the slides located below the magazine and whereby a coin inserted into a slot of its respective denomination interconnects the operating slide member with predetermined change slides for corresponding reciprocal movement, the bottom plate having openings formed therethrough registrable with the slots when the slides are in coin releasing position, means adapted to receive coins and to segregate the coins into denominations corresponding to the denominations which the slots are adapted to receive and to deliver coins of all but those of the smallest denomination to their respective slots in the

change slides and slide member and the coins of the smallest denomination to the magazine, means for reciprocating the slide member and change slides connected thereto by coins located in registered slots between the coin receiving and coin releasing positions, a detector finger mounted on the magazine for reciprocal movement between a position within the magazine and a position removed therefrom, means borne by the slide member having controlling connection with the finger and retracting the finger from the magazine upon movement of the slide member from coin receiving position, and means connected to the finger and to the coin receiving means blocking reception of coins requiring change by the coin receiving means when the finger is within the magazine.

3. A coin conditioned change making and control mechanism comprising a coin detector adapted to accept coins of predetermined denomination, to reject coins of other denominations and spurious objects, and to segregate accepted coins into their respective denominations; a rotatable operating shaft; coin chutes individual to the denominations of coins accepted by the detector positioned to receive coins of their respective denominations; a magazine for change making coins, the coin chute for coins of the smallest denomination being arranged to direct such coins into the magazine; a plurality of superimposed change making slides mounted below the magazine and below the coin chutes for independent reciprocal movement between coin receiving and coin releasing positions, there being a change making slide for each of the predetermined coin denominations except the smallest denomination; an operating slide mounted adjacent to the change making slides for corresponding reciprocal movement, each change making slide having a slot formed therein positioned to receive coins from a coin chute of its respective predetermined denomination when the slide is in coin receiving position, the slots of each slide being extended into the operating slide and into any slides of a lesser denomination whereby a coin located in a slot of a slide interconnects that slide and any slides of a lesser denomination with the operating slide, and the change making slides having aligned pockets therein in registry with the magazine when the slides are in coin receiving position, the pocket of each slide being of a size in combination with the pockets of any slide with which it is connected by coin in slot engagement to receive from the magazine a quantity of coins sufficient for change making purposes for the coin engaged in the slot; a drive linkage interconnecting the shaft and the operating slide and translating shaft oscillation into reciprocation of the operating slide and all change slides connected thereto by coin and slot engagement between coin receiving and coin releasing positions; a change receptacle positioned to receive coins contained by the pockets of the reciprocated slides when said slides are moved to coin releasing position; a coin container positioned to receive coins from the coin slots when said slides are in coin releasing position; and a control linkage operably interconnecting the coin detector and the coin detector finger and blocking the coin detector against receipt of coins of denominations requiring change when the detector finger is within the magazine.

4. A coin conditioned change making and control mechanism comprising a coin detector adapted to accept coins of predetermined denomination, to reject coins of other denominations and spurious objects, and to segregate accepted coins into their respective denominations; a rotatable operating shaft; coin chutes in-

dividual to the denominations of coins accepted by the detector positioned to receive coins of their respective denominations segregated by the detector; a magazine for change making coins, the chute for coins of the smallest denomination being arranged to direct such coins into the magazine; a coin detector finger mounted for reciprocal movement between a position in the magazine in predetermined spaced relation to the bottom thereof and a position removed therefrom; a plurality of superimposed change making slides mounted below the magazine and below the coin chutes for independent reciprocal movement between coin receiving and coin releasing positions, there being a change making slide for each of the predetermined coin denominations except the smallest denomination; an operating slide mounted adjacent to the change making slides for corresponding reciprocal movement, each change making slide having a slot formed therein positioned to receive coins from a coin chute of its respective predetermined denomination when the slide is in coin receiving position, the slots of each slide being extended into the operating slide and into any slides of a lesser denomination whereby a coin located in a slot of a slide interconnects that slide and any slides of a lesser denomination with the operating slide, and the change making slides having aligned pockets therein in registry with the magazine when the slides are in coin receiving position, the pocket of each slide being of a size in combination with the pockets of any slide with which it is connected by coin in slot engagement to receive from the magazine a quantity of coins sufficient for change making purposes for the coin engaged in the slot; a drive linkage interconnecting the shaft and the operating slide and translating shaft oscillation into reciprocation of the operating slide and all slides connected thereto by coin and slot engagement between coin receiving and coin releasing positions; a change receptacle positioned to receive coins contained by the pockets of the reciprocated slides when said slides are moved to coin releasing position; a coin container positioned to receive coins from the coin slots when said slides are in coin releasing position; and a control linkage operably interconnecting the coin detector and the coin detector finger and blocking the coin detector against receipt of coins of denominations requiring change when the detector finger is within the magazine.

5. A coin conditioned change making and control mechanism comprising a coin detector adapted to accept coins of predetermined denomination, to reject coins of other denominations and spurious objects, and to segregate accepted coins into their respective denominations; coin chutes individual to the denominations of coins accepted by the detector positioned to receive coins of their respective denominations from the detector; a rotatable operating shaft; a releasable catch locking the shaft against rotation; catch release means integral with the shaft adapted to receive coins of the smallest denomination from such coins' respective chute in a position to engage the catch and to release the shaft for rotation by camming action of the coin in said means upon the catch; a magazine for change making coins arranged to receive coins of the smallest denomination from the catch release means upon shaft rotation; a coin detector finger mounted for movement to and from the magazine at a position in spaced relation to the bottom thereof; a plurality of superimposed

change making slides mounted below the magazine and below the coin chutes for independent reciprocal movement between coin receiving and coin releasing positions, there being a change making slide for each of the predetermined coin denominations except the smallest denomination; an operating slide mounted adjacent to the change making slides for corresponding reciprocal movement, each change making slide having a slot formed therein positioned to receive coins from a coin chute of its respective predetermined denomination when the slide is in coin receiving position, the slots of each slide being extended into the operating slide and into any slides of a lesser denomination whereby a coin located in a slot of a slide interconnects that slide and any slides of a lesser denomination with the operating slide, and the change making slides having aligned pockets therein in registry with the magazine when the slides are in coin receiving position, the pocket of each slide being of a size in combination with the pockets of any slide with which it is connected by coin in slot engagement to receive from the magazine a quantity of coins sufficient for change making purposes for the coin engaged in the slot; a drive linkage interconnecting the shaft and the operating slide and translating shaft oscillation into reciprocation of the operating slide and all slides connected thereto by coin and slot engagement between coin receiving and coin releasing positions; a change receptacle positioned to receive coins contained by the pockets of the reciprocated slides when said slides are moved to coin releasing position; a coin container positioned to receive coins from the coin slots when said slides are in coin releasing position; a cam borne by the operating slide engageable with the detector finger, removing said finger from the magazine upon movement of the slide to coin releasing position and releasing said finger for gravitational return to the magazine upon return of the slide to coin receiving position; and a control linkage operably interconnecting the coin detector and the coin detector finger and blocking the coin detector against receipt of coins of denominations requiring change when the detector finger is within the magazine.

6. In combination with a coin detector adapted to accept coins of predetermined denominations, to reject coins of other denominations and spurious objects, and to segregate accepted coins into their respective denominations; a housing enclosing the coin detector; a shaft mounted for oscillatory rotation in the housing and extended therefrom; means for imparting rotation of the shaft connected to the shaft externally of the housing, a releasable catch mounted in the housing and locking the shaft against rotation; a disc member borne by the shaft and having a receptacle formed therein adapted to receive coins of the smallest denomination from the coin detector in a position to engage the catch and to release the shaft for rotation by camming action of such a coin upon the catch; coin chutes arranged to receive accepted coins of predetermined denomination other than those of the smallest denomination from the coin detector; a magazine mounted in the housing in a position to receive coins of the smallest accepted denomination from the disc; a coin detector finger mounted on the magazine for oscillatory movement between a position in the magazine and a position removed from the magazine; a plurality of superimposed change making slides mounted below the magazine and

below the coin chutes for independent reciprocal movement between corresponding coin receiving and coin releasing position, there being a change making slide for each of the predetermined coin denominations except the smallest denomination; an operating slide mounted adjacent to the change making slides for corresponding reciprocal movement, each change making slide having a slot formed therein positioned to receive coins from a coin chute of its respective predetermined denomination when the slide is in coin receiving position, the slots of each slide being extended into the operating slide and into any slides of a lesser denomination whereby a coin located in a slot of a slide interconnects that slide and any slides of a lesser denomination with the operating slide, and the change making slides having aligned pockets therein in registry with the magazine when the slides are in coin receiving position, the pocket of each slide being of a size in combination with the pockets of any slide with which it is connected by coin in slot engagement to receive from the magazine a quantity of coins sufficient for change making purposes for the coin engaged in the slot; a drive linkage interconnecting the shaft and the operating slide and translating shaft oscillation into reciprocation of said operating slide and all slides connected thereto by coin and slot engagement between coin receiving and coin releasing positions; resilient means mounted in the housing, connected to the drive linkage, and urging the reciprocated slides into coin receiving position; a plate mounted below the lowermost slide and apertured in a position for the gravitational release of coins from the slots and change making coins from the pockets when the reciprocated slides are in coin releasing position; a cam having driven connection with the operating slide engageable with the detector finger, removing said finger from the magazine upon movement of said slide to coin releasing position and releasing said finger for gravitational return to the magazine upon return of the slide to coin receiving position; and a control linkage operably interconnecting the coin detector and the coin detector finger and blocking the coin detector against receipt of coins of denominations requiring change when the detector finger is within the magazine.

7. In a change making device; the combination of a substantially erect coin tube; a plurality of superimposed change making slides mounted below the magazine for independent reciprocal movement between coin receiving and coin releasing positions; an operating slide mounted adjacent to the change making slides for corresponding reciprocal movement, each of the change making slides having a slot formed therein adapted to receive a coin of a predetermined denomination when the slide is in coin receiving position, each of the slides having a change pocket therein vertically aligned in registration with the magazine when the slides are in coin receiving position, the slot of each slide extending into the operating slide whereby receipt of a coin of its respective denomination into the slot interconnects the change making slide and the operating slide for corresponding movement; means for reciprocally positioning the operating slide and all slides connected therewith by coin and slot engagement between coin receiving and coin releasing position; and a plate underlying the operating slide and apertured gravitationally to release coins contained

in the slots and in the pockets when the reciprocated slides are in coin releasing position.

8. A device adapted to receive coins of a plurality of predetermined sizes all but the smallest of which are of values multiples of the smallest and to release for motivation a mechanism having driven connection therewith upon receipt of any of said coins of predetermined size and to return change in a sum less than the value of the coin received by the value of the smallest of said predetermined coins comprising a coin receiver adapted to accept coins of a plurality of predetermined denominations and to segregate the coins accepted; a rotatable operating shaft; a releasable catch locking the shaft against rotation beyond a predetermined limit; means mounted on the shaft adapted to receive coins of the smallest denomination from the coin receiver and to carry such coins through an arc of rotation of the shaft in a position in which the coins cam the catch from locking position; a coin magazine positioned to receive the coins of the smallest denomination from the carrying means at the end of their arc of travel therein; coin chutes connected to the coin detector individual receiving coins of predetermined denomination larger than the coins directed to the magazine; a plurality of superimposed change making slides mounted below the magazine and below the coin chutes for independent reciprocal movement between coin receiving and coin releasing positions there being a change making slide for each of the predetermined coin denominations accepted except the smallest denomination; an operating slide mounted adjacent to the change making slides for corresponding reciprocal movement, each change making slide having a slot formed therein positioned to receive coins from a coin chute of its respective predetermined denomination when the slide is in coin receiving position, the slots of each slide being extended into the operating slide and into any slides of a lesser denomination, and the change making slides having aligned pockets therein in registry with the magazine when the slides are in coin receiving position, the pocket of each slide being of a size in combination with the pockets of any slide to which it is connected by coin-in-slot engagement to receive from the magazine a quantity of coins sufficient for change making purposes for the coin engaged in the slot; a drive linkage interconnecting the shaft and the operating slide and translating shaft oscillation into reciprocation of the operating slide and any slides connected thereto by coin-and-slot engagement between a coin receiving position below the magazine and a coin releasing position; a bottom plate located below the slides forming bottoms for the coin slots and coin pockets of the slides, said plate having openings formed therein registerable with the slots and pockets respectively when the slides are in coin releasing position; a linkage interconnecting the operating slide and the catch adapted to release the catch in response to movement of the operating slide and change slide connected thereto to coin releasing position; a detector mounted for oscillatory movement between a position within the magazine and a position removed therefrom; cam means borne by the operating slide engageable with the detector and retracting the detector from the magazine upon movement of the operating slide to coin releasing position; a rejector finger mounted for reciprocal movement between a position in blocking relation to the

coin receiver and a position removed therefrom; and a linkage interconnecting the detector and the rejecting finger and positioning said rejecting finger in blocking relation to the receiver when the detector is positioned within the magazine, the detector being blocked from return to the magazine when there are coins in the magazine in excess of a predetermined number.

9. A coin conditioned change making and control mechanism comprising a coin detector adapted to accept coins of a plurality of predetermined denominations and to segregate the accepted coins into their respective denominations; a rotatable operating shaft having a predetermined rest position; a releasable catch locking the shaft against rotation beyond a predetermined distance from rest position; means mounted on the shaft to receive coins of the lowest acceptable denomination from the detector in a position adapted to engage the catch and cam the catch from locking position in response to rotation of the shaft from rest position; a coin magazine positioned to receive the accepted coins of the smallest denomination from the catch releasing means mounted on the shaft; a plurality of change slides individual to the acceptable denominations of coins except the lowermost thereof mounted in stacked relation below the magazine for independent movement between coin receiving and coin releasing positions and having pockets formed therein in registry with the magazine when the slides are in coin receiving position to receive predetermined numbers of coins from the magazine; an operating member mounted adjacent to the slides for movement between the coin receiving and coin releasing positions; a drive linkage responsive to oscillation of the shaft having driving connection with the operating member, the operating member and the slides having aligned coin slots therein adapted to receive coins of predetermined denominations when the operating member and slides are in coin receiving position with the pockets of the slides located below the magazine whereby a coin inserted into a slot of its respective denomination interconnects the operating member with predetermined change slides for corresponding reciprocal movement; coin directing means adapted to receive coins of all but the smallest acceptable denomination from the detector and to direct the coins into slots in the operating member and slides individual to the coins respective denominations whereby such coins provide driving connection between the operating member and their respective slides having predetermined change therefor in their pockets; and a catch release linkage interconnecting the change slides and the catch adapted to release the catch in response to movement of any slide from coin receiving position.

10. In combination with a coin magazine having a downwardly disposed opening, a plurality of change slides mounted in stacked relation below the magazine for independent reciprocal movement between coin receiving and coin releasing position and having pockets formed individually therethrough in positions simultaneously registerable with the opening in the magazine when the slides are in coin receiving position, a bottom plate slidably receiving the change slides thereon, said plate forming a bottom to the pockets when the plates are in rest position and providing a discharge opening in registry with the pockets when the slides are in coin releasing positions, an operating slide mem-

ber mounted for reciprocal movement in stacked relation to the change slides, said change slides and slide member having coin slots formed therein adapted to receive coins of predetermined denominations in registration when the slide member and slides are in coin receiving position with the pockets of the slides located below the magazine and whereby a coin inserted into a slot of its respective denomination interconnects the operating slide member with predetermined change slides for corresponding reciprocal movement, the bottom plate having openings formed therethrough registrable with the slots when the slides are in coin releasing position, means adapted to receive coins and to segregate the coins into denominations corresponding to the denominations which the slots are adapted to receive and to deliver coins of all but those of the smallest denomination to their respective slots in the change slides and slide member and the coins of the smallest denomination to the magazine, and means for reciprocating the slide member and change slides connected thereto by coins located in registered slots between the coin receiving and coin releasing positions.

11. In a coin conditioned change making and control mechanism, a coin detector adapted to accept coins of a plurality of predetermined denominations and to segregate the accepted coins into their respective denominations, a shaft rotatably mounted below the detector, a disc member mounted concentrically on the shaft having a peripherally disposed hook portion, a detent pivotally mounted for reciprocal movement to and from the path of travel of the hook portion of the disc member incident to shaft rotation, means urging the detent into said path of travel of the hook portion, the disc member having a coin receiving slot formed therein adapted to receive coins of the lowest denomination from the detector in a position adapted to cam the detent from the path of travel of the hook portion, a magazine for change making coins, change making means adapted to receive coins of all but the lowest denomination from the detector, operably connected to the shaft by receipt of such coins, movable between a position in which change making coins are received from the magazine and a change delivering position, and a detent release linkage interconnecting the change making means and the detent moving the detent from the path of travel of the hook portion of the disc member in response to movement of the change making means from the position in which change making coins are received from the magazine.

12. A coin conditioned change making and control mechanism comprising a coin detector adapted to accept coins of predetermined denominations, to reject the coins of other denominations and spurious objects, and to segregate accepted coins into their respective denominations; coin chutes individual to the denominations of coins accepted by the detector positioned to receive coins of their respective denominations from the detector; a rotatable operating shaft; a releasable catch locking the shaft again operating rotation but permitting a limited idle movement of the shaft; catch release means integral with the shaft adapted to receive coins of the smallest denomination from such coins' respective chute in a position to engage the catch and to release the shaft for rotation by camming action of the coin in said means upon the shaft; a magazine for change

making coins arranged to receive coins of the smallest denomination from the catch release means upon shaft rotation; change making means mounted for reciprocal movement between a position adapted to receive coins from the magazine and a coin releasing position; operating means mounted adjacent to the change making means for corresponding reciprocal movement therewith, the change making means and the operating means having aligned slots therein positioned to receive coins from a coin chute of a denomination requiring change to interconnect the delivering means and the operating means in driving relation; a drive linkage interconnecting the shaft and the operating means and translating shaft oscillation into reciprocation of the operating means; and a catch release linkage interconnecting the change making means and the catch releasing the catch upon movement of the change making means from coin receiving position.

13. In a coin conditioned change making and control mechanism, a coin detector adapted to accept coins of a plurality of predetermined denominations and to segregate the accepted coins into their respective denominations, a shaft rotatably mounted below the detector, a disc member mounted concentrically on the shaft having a peripherally disposed hook portion, a detent pivotally mounted for reciprocal movement to and from the path of travel of the hook portion of the disc member incident to the shaft rotation, means urging the detent into said path of travel of the hook portion, the disc member having a coin receiving slot formed therein adapted to receive coins of the lowest denomination from the detector in a position adapted to cam the detent from the path of travel of the hook portion, a magazine for change making coins arranged to receive coins of the smallest denomination from the disc member upon shaft rotation, a plurality of superimposed change making slides mounted below the magazine and below the coin chutes for independent reciprocal movement between coin receiving and coin releasing positions, there being a change making slide for each of the predetermined coin denominations except the smallest denomination, an operating slide mounted adjacent to the change making slides for corresponding reciprocal movement, each change making slide having a slot formed therein positioned to receive coins from a coin chute of its respective predetermined denomination when the slide is in coin receiving position, the slots of each slide being extended into the operating slide and into any slide of a lesser denomination whereby a coin located in a slot of a slide interconnects that slide and any slides of a lesser denomination with the operating slide, and the change making slides having aligned pockets therein in registry with the magazine when the slides are in coin receiving position, the pocket of each slide being of a size in combination with the pockets of any slide with which it is connected by coin-in-slot engagement to receive from the magazine a quantity of coins sufficient for change making purposes for the coin engaged in the slot, a drive linkage interconnecting the shaft and the operating slide and translating shaft oscillation into reciprocation of the operating slide and all slides connected thereto by coin and slot engagement between coin receiving and coin releasing positions, and a detent release linkage

interconnecting the detent and the change making slide for the smallest denomination of coins requiring change moving the detent from the path of movement of the hook portion of the disc member in response to movement of said change making slide from coin receiving positions.

HARRY S. CHILDERS.
